[57] **CLAIM**

The ornamental design for a nail gun housing, as shown and described.

DESCRIPTION

FIG. 1 is a perspective view of the nail gun housing according to the invention;

FIG. 2 is a left side view;

FIG. 3 is a right side view;

FIG. 4 is a front view;

FIG. 5 is a rear view;

FIG. 6 is a top view; and,

FIG. 7 is a bottom view.

The nail magazine for the housing is shown in dotted lines for environmental orientation but forms no part of the design.
